BROOCH OR SIMILAR ARTICLE

Lincoln L. Ciampa, New York, N. Y., assignor to
United States Electric Manufacturing Corpora-
tion, New York, N. Y., a corporation of New
York

Application September 25, 1952, Serial No. 21,588

Term of patent 14 years

(Cl. D45—19)

To all whom it may concern:

Be it known that I, Lincoln L. Ciampa, a citizen
of the United States of America, residing in the
Borough of Manhattan, in the county of New
York, city and State of New York, have invented
a new, original, and ornamental Design for a
Brooch or Similar Article, of which the following
is a specification, reference being had to the ac-
companying drawing, forming part thereof.

In the drawing

Fig. 1 is a front elevational view of a brooch
showing my new design;

Fig. 2 is a rear elevational view thereof;

Fig. 3 is a bottom plan view thereof;

Fig. 4 is a side elevational view thereof; and
Fig. 5 is a top plan view thereof.

The dominant features of my design reside in
those portions shown in full lines.

I claim:

The ornamental design for a brooch or similar
article, substantially as shown and described.

LINCOLN L. CIAMPA.
